*E. Kingsland,
Brick Machine,*

No 14,873.

Patented May 13, 1856.

UNITED STATES PATENT OFFICE.

EDMUND KINGSLAND, OF NEW YORK, N. Y.

BRICK-MACHINE.

Specification of Letters Patent No. 14,873, dated May 13, 1856.

To all whom it may concern:

Be it known that I, EDMUND KINGSLAND, of the city, county, and State of New York, have invented certain new and useful Improvements in Machinery for Making Bricks; and I do hereby declare that the following is a full, clear, and exact description of the same, reference being had to the accompanying drawing, forming part of this specification, in which—

Figure 1, is a vertical section of a brick machine constructed according to my invention, taken in a plane perpendicular to the axis of the mold cylinder. Fig. 2, is a section of the mold cylinder in a plane passing through its axis. Fig. 3, is a plan of the machine. Fig. 4, is a face view of what I call the "finisher."

Similar letters of reference indicate corresponding parts in the several figures.

This invention consists, firstly, in an oscillating finisher having two sets of bearings, of which one set is rigidly fixed and the other yielding, and operating substantially as hereinafter described, in combination with a revolving mold cylinder for the purpose of finishing the bricks with flat surfaces on their outer faces.

It consists secondly, in certain means of varying the depth of all the molds in the mold cylinder simultaneously, for the purpose of varying the thickness of the bricks.

To enable others skilled in the art to make and use my invention I will proceed to describe its construction and operation.

A, A, is the framing of the machine containing bearings for the driving shaft B, the shaft C, of the mold cylinder, the pressure roller E, and the finisher F.

D, is the mold cylinder which has the outer faces of the molds a, a, flat, as shown in Fig. 1.

b, b, are the pistons for forcing the clay out of the molds. The pistons of every row running longitudinally of the cylinder are all attached to one of a series of bars G, G, which are fitted within the cylinder to work in and out radially and provided with studs b', b', at each end, protruding from the ends 50 of the cylinder to come in contact with two pairs of rollers c and d, shown dotted in Fig. 1, arranged on stationary axes on both sides of the machine for the purpose of driving in the pistons before filling the molds, 55 and driving them out again to expel the finished bricks.

The method of arranging and operating the pistons, as far as thus described is substantially like that in some other machines, but the method of supporting the pistons 60 during the pressure of the brick, which also admits of the variation of the depth of the molds, is different, as I will now describe. The inner edges of the piston bars G, G, are inclined in opposite directions from the 65 middle of their length toward their extremities, as shown at e, e, Fig. 2, and the mold cylinder shaft C is fitted with two metal frustums of cones H, H, the profiles of which correspond with the inclinations e, e, 70 on the inner faces of the piston bars G, G, the said cones serving as a bearing for the piston bars while the pistons are at the bottom of the molds and during the compression of the clay therein. By moving these 75 cones toward or from each other, the piston bars are caused to find a bearing, with the pistons at a less or greater depth within the mold, and thus to vary the thickness of the bricks. To effect the movement of the cones 80 for this purpose, I make the cylinder shaft C, to which the cylinder is firmly secured, hollow, and fit to suitable bearings therein, a small shaft C', upon which are right and left handed screws f, f, fitted with nuts g, g, 85 which are attached to the cones H, H, by arms r', r', passing through slots j, j, in the shaft. The shaft C'' is fitted to the shaft C, so as to be capable of turning but not 90 moving longitudinally therein, but the nuts are allowed to move longitudinally by providing suitable cavities within the shaft, though they are prevented from turning, by the arms i, i, in the slots j, j. The shaft shaft C' is provided with a suitable handle 95 k, at one end by which to turn it and by turning it, the nuts are caused to approach or recede from each other, according to the direction in which the shaft is turned, and the cones being connected to the nuts, move 100 also. When the adjustment of the cones is varied, the position of the roller e, by which the pistons are forced into the molds will require to be varied, as it is desirable that the pistons should be pushed just to their 105 bearing. The cylinder is driven by a pair of gears g, g, from the main shaft B.

The pressure roller E, is applied and operates in the same manner as the first pressure roller of other brick machines of similar character working in fixed bearings and being driven by a pair of gears l, l, from 110

the cylinder shaft C, so that its periphery rotates at the same speed as the periphery of the mold cylinder. This roller presses the clay into the molds to form the bricks 5 but leaves them with a rounded surface.

The finisher F which is employed to give the final pressure to the clay in the molds, consists of a segment of a cylinder whose radius may be about equal to the radius of 10 a circle circumscribing the mold cylinder. This segment is of the same length as the mold cylinder. It is furnished with a pair of journals o, o, and also with another pair of journals p, p. The relative positions of 15 these journals are shown in Fig. 1. The journals o, o, are some distance from the arc of the segment and are in a plane which is normal to the vertex of the arc. The journals p, p, are nearly close to the arc 20 at one extremity thereof. The journals o, o, are received in boxes n, n, which are so arranged that the segment formed finisher will bear at the vertex or central line of its 25 arc on the face of the mold cylinder. The position of the boxes of these journals determines the position of the bearings for the journals p, p. The latter bearings are 30 fixed but the boxes n, n, are fitted to slide to a limited extent toward and from the mold cylinder, and have springs m, m, applied to them to give the finisher heavy but yielding pressure to keep its face in contact with the mold cylinder but to allow it to oscillate slightly from its journals p, p, 35 as is required by the polygonal character which the mold cylinder is caused to have by the flattening of the faces of the molds. The molds containing the clay which has been pressed in them, by the roller E, in 40 passing the face of the finisher, cause the clay to receive therefrom the final pressure and also to have a flat form given to its outer face. The finisher F has no other movement than the slight oscillating movement 45 that is produced by the flat faces of the molds on the mold cylinder. By making the cylinder with flat faced molds, as described, and employing the finisher F in connection with it, I am enabled to make 50 flat faced bricks on a mold cylinder of small diameter and keep the machine in a smaller compass than other brick machines using mold cylinders, as the cylinders of those machines are generally made as large as 55 practicable so that the outer faces of the bricks may be made nearly flat by a finishing roller working in fixed bearings.

I, is a dust box containing dust for dusting the pistons and insides of the molds, 60 arranged at a suitable point above the mold cylinder and having an open bottom fitted with a cylindrical screen K, which receives a rotary motion through a band r, running to a pulley s, on its shaft, from the pressure 65 roller E, (see Fig. 3). Below the screen K,

is a revolving box L secured to a shaft arranged in suitable bearings. This box has compartments in the form of segments of a cylinder. The dust sifted by the screen K falls into the compartments of the box L, 70 and by the revolution of the latter which has a fan like action, is thrown in a thin shower into the molds just before they arrive at the hopper M, where they receive the clay. The box L receives its rotary motion 75 through a band t, from a pulley u, on the main shaft B, running to a pulley v, on its own shaft.

W, is an endless moving apron arranged under the mold cylinder to receive the bricks 80 from the molds and convey them away.

O, is a box in which the clay is placed for making the bricks. This box is provided with an inclined perforated bottom P, which receives a reciprocating motion through two 85 connecting rods w, w, from two cranks x, x, on a shaft Q. In place of this reciprocating motion, a rotary motion may be used. Above the perforated bottom and nearly touching it, there are stationary bars R, R, 90 secured across the box. The perforated moving bottom P, of the clay box O, extends some distance through the upper end of the box toward the hopper M and over it, is placed an open bottomed box S, containing 95 coal dust, and still higher is placed an open bottomed sand box T, containing sand. Said boxes S and T fitting closely to the perforated bottom P. Some distance below the perforated bottom P, is placed an 100 endless apron V, which works on two rollers y, y. This apron inclines in the same direction as the said bottom, viz: upward toward the hopper M. Between the apron V and the perforated bottom of the clay box 105 and nearly under the coal box S, is placed the shaft Q before mentioned, which is intended to be driven in any convenient manner. This shaft Q carries a number of radial beaters 4, 4. A little higher up the 110 inclined apron is a shaft U which stands nearly under, only a little higher up the apron than the sand box, carrying two circular heads 5, 5 to which are attached a number of beaters b, b, arranged parallel 115 with the shaft. The clay is prepared for being molded by being placed in the box O, where it is ground up, between the perforated bottom P and the stationary bars R, R, and forced through the perforations 120 in the bottom P on to the apron V, and is carried by the apron under the coal box S, where it is worked up again by the beaters 4, 4, on the shaft Q and the coal dust falling through the bottom P are mixed with it by the said beaters after which it receives the sand from the sand box T, and is again worked up by the long beaters b, b.

The operation of forming the bricks is as follows. The clay after having been worked 125

and tempered as above described, is deposited by the apron V in the hopper M from whence it is forced into the molds by the revolution of the mold cylinder toward 5 the pressure roller E, as is indicated by the arrow in Fig. 1, and is compressed in the molds by the said rollers E, as they severally arrive opposite the said roller. The molds now filled with clay, pass in contact with 10 the finisher F, by which the final pressure and flattening of the outer surfaces of the bricks is effected as hereinbefore described; from the finisher the molds move onward until the ends of their respective piston bars 15 G, G come in contact with the rollers d, d, the action of which drives out the bricks and deposits them on the apron W. The empty molds then move onward until the ends b, of their piston bars G, come in contact with 20 the roller e, and at about the same time as this is effected the dust is sprinkled into the mold by the action of the revolving box or fan I, when the mold is in a state to be

recharged with clay as it moves on under the hopper. 25

What I claim as my invention and desire to secure by Letters Patent, is,

1. The oscillating finisher F, provided with a pair of fixed and a pair of movable bearings, and operating substantially as 30 herein described, in combination with a mold cylinder containing flat faced molds, for the purpose of finishing the bricks with flat outer surfaces, as herein set forth.

2. The employment, for varying the depth 35 of all the molds simultaneously to vary the thickness of the bricks, of the two cones H, H, the right and left handed screw shaft C', and the nuts g, g, all applied to the mold cylinder shaft and operating substantially 40 as herein described, in combination with the inclined edges e, e, on the piston bars G, G.

EDMUND KINGSLAND.
